United States Patent Office.

EDWARD P. ROCHE, OF BATH, MAINE.

Letters Patent No. 95,936, dated October 19, 1869.

IMPROVEMENT IN HOOKS AND EYES.

The Schedule referred to in these Letters Patent and making part of the same.

To all to whom these presents shall come:

Be it known that I, EDWARD P. ROCHE, of Bath, in the county of Sagadahoc, and State of Maine, have made an invention of a new and useful Hook-and-Eye Fastening; and do hereby declare the following to be a full, clear, and exact description thereof, due reference being had to the accompanying drawings, making part of this specification, and in which—

Figure 1 is a vertical and outside view of any portion of clothing provided with my invention.

Figure 2 is a horizontal section of the same.

The object of the invention is to produce a durable, convenient, cheap, and effective fastening for any portion of personal clothing.

The ordinary hooks and eyes are continually wearing off, and require considerable care to keep them sewed on. They require to be sewed on separately, and care is required to place them evenly; and when the garment fits tightly it will be drawn outward, between the hooks and eyes, giving it an untidy appearance.

In the drawings before mentioned, as accompanying this specification, and which illustrate my invention—

A A represent any portions of personal clothing, which are to be secured together;

a a, &c., the hooks; and

b b, &c., the eyes.

As will be observed from the drawings, the hooks are all formed of one continuous piece of wire, and the eyes the same. The hooks and eyes, in this manner, may be manufactured in any required length, and cut off as wanted for use; the hooks and eyes being cut off to the required length, corresponding to the length of the place to be secured, and sewed into the garment

itself, and can be much more securely fastened than the ordinary hooks and eyes.

The hooks and eyes, being made from good spring or tempered wire, and flattened if necessary, will form an elastic yet firm connection between the parts to be fastened, and the continuation of the wire will prevent the drawing asunder of the material of which the garment is composed between the points of connection.

From the above description of the object, and the manner of carrying into effect my invention, the intelligent reader will readily comprehend the convenience, simplicity, cheapness, and desirableness of the device.

I am aware that hooks and eyes have been formed from continuous strips of sheet-metal, stamped, punched, and bent up into shape; but such devices are difficult to manufacture, and require the use of special machinery of various kinds, while they cannot be made of the small dimensions which are at times required, without rendering them too weak to be practically useful. I am also aware that wire has before been bent into various shapes for the purpose of fastening garments; but I am not aware that hooks and eyes, such as those shown by me, have been formed in a continuous series from strips of wire.

What I claim, therefore, and desire to secure by Letters Patent, is—

As a new manufacture, hooks and eyes, formed from continuous strips of spring or tempered wire, bent into the shape substantially such as herein shown and described.
